DESIGN FOR A LINE BLINDING L-FITTING

Leland S. Hamer, Long Beach, Calif.

Application January 19, 1948, Serial No. 143,882

Term of patent 14 years

(Cl. D78—1)

To all whom it may concern:

Be it known that I, Leland S. Hamer, a citizen of the United States, residing in the city of Long Beach, county of Los Angeles, and State of California, have invented a new, original, and ornamental Design for a Line Blinding L-Fitting, of which the following is a specification, reference being had to the accompanying drawing, forming a part thereof.

Fig. 1 is a perspective view of the line blinding L-fitting, showing my new design, taken from one side of the fitting and showing the upper portion thereof, and Fig. 2 is a perspective view of the line blinding L-fitting taken from the other side of the fitting and showing the lower portion thereof.

I claim:

The ornamental design for a line blinding L-fitting, as shown and described.

LELAND S. HAMER.
